Primary Examiner — Philip S Hyder*Assistant Examiner* — Darlington Ly(74) *Attorney, Agent, or Firm* — Kofi Schulterbrandt;
Michael P. Leary(57) **CLAIM**

The ornamental design for a rivet setting tool, as shown and described.

DESCRIPTION

FIG. 1 is top, front and right-side perspective view of an rivet setting tool showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the drawings illustrate portions of the rivet setting tool that forms no part of the claimed design.

1 Claim, 7 Drawing Sheets(56)
